EDGAR U. RICE, OF WESTFIELD, NEW JERSEY, ASSIGNOR TO WESTERN ELECTRIC COMPANY, INCORPORATED, OF NEW YORK, N. Y., A CORPORATION OF NEW YORK

SERVING DEVICE

Application filed March 24, 1930. Serial No. 438,267.

This invention relates to serving devices and more particularly to devices for serving a plurality of strands upon a single object.

An object of the invention is to provide a simple and efficient serving device where-in the supplies for a strand may be replenished without interfering with any remaining strand.

In a preferred embodiment of the device, a cable to be spirally wound with metal tape is passed axially through a rotatable serving head consisting of a circular plate, which is provided with two pads of tape, the one 10 annular and another a substantially solid 15 circular pad. These pads are mounted on opposite sides of the rotating plate and the tapes are served from them simultaneously to a common point where they are wrapped around the cable with an overlapping lay, 20 the tape from the annular pad being superposed upon that served from the circular pad. In this way, as either of the pads becomes exhausted, a fresh pad from associated magazines may be used to replace it 25 without in any way interfering with the tape leading from the other pad.

The invention will be better understood from the following detailed description, read in connection with the accompanying drawings forming a part thereof, in which

Fig. 1 is an end elevation of a serving apparatus embodying features of the invention, the magazines having been omitted for clarity;

Fig. 2 is a fragmentary enlarged section taken on the line 2—2 of Fig. 1, and including the magazines omitted from Fig. 1;

Fig. 3 is a fragmentary section taken on the line 3—3 of Fig. 1 and enlarged to correspond with Fig. 2; and

Fig. 4 is a section taken on the line 4—4 of Fig. 1 and enlarged to correspond with Figs. 2 and 3.

Referring to the drawings in which similar parts are indicated by identical reference numerals, a serving apparatus, generally designated by the numeral 10 (Fig. 1), is supported upon a pair of parallel foundation bars 11—11 by a platform 12. The platform is provided at each end with braek-

ets 14—14 to which is secured, by means of suitable bolts 15—15, a magazine 16 (Fig. 2). The magazine consists of a substantially circular plate having a central axially disposed aperture 19 which is designed to accommodate an object, core or cable 20 during its passage through the serving apparatus 10 in a manner to be described hereafter. The plate 16 is provided on an inner side thereof with an annular flange 21 of sufficient width to accommodate any desired number of annular tape pads 22, 22, which may form a reserve supply of material to be served upon the cable 20.

On the opposite side of the platform 12, a pair of brackets 23—23 (Fig. 2) is secured, the brackets being provided with suitable bolts 24—24 for the purpose of securing thereto a second magazine 26. The magazine is provided with a central axially disposed aperture 27 about which is formed a projecting tube 28 which furnishes a support for any desired number of circular tape pads 30, 30 sufficient to form a reserve supply for the apparatus. A circular drum or guard 32 is securely mounted upon the platform 12 by suitable flanges 34 and is provided with oppositely disposed and radially projecting annular flanges 35—35. At opposite extremities of the supporting flanges 34, the annular flanges support spaced shafts 37—37 (Fig. 2). The shafts are suitably journaled in supporting brackets 38, 38 and each is formed with a roller 39. At the top of the guard 32 (Fig. 1), at spaced points corresponding to the positions of the rollers 39, 39, are mounted oppositely disposed rollers 42, 42 which are formed upon shafts 43, 43 suitably journaled in the annular flanges 35—35. A serving head 44 is rotatably mounted within the guard 32 and consists of a circular plate 46 having peripherally disposed teeth 47 which are engaged by a drive chain 48, and an annular bearing flange 50 which bears upon the rollers 39, 39. The head is rotatably secured thereupon and between the upper rollers 42, 42 so as to be freely rotatable about a fixed axis. The fixed axis is coincident with a central aperture 51 with which the plate 46 is provided and the plate is there provided with 100

an axially extending tubular portion 52 for the purpose of accommodating the cable 20 in its passage through the plate. In the rear of the machine a bearing support 54 (Fig. 1) is 5 provided, upon which is mounted a drive sprocket 55 keyed to a drive shaft 56 which is rotatably driven from any suitable source of power (not shown). It will be understood that the chain 48 is driven by the sprocket 55 10 to rotate the plate 46, passing over an idler sprocket 58 mounted upon a shaft 59 in the bearing support and which may be adjusted by any suitable means (not shown) to control the tension in the chain 48. A spacing disc 15 60 (Fig. 2) is mounted upon the tubular portion 52 of the circular plate and is provided with a projecting sleeve 62 on which is formed a retaining rim 63 by means of which a circular pad holder 64 is held in place upon the 20 sleeve. At opposite points spaced from the central aperture 51, threaded set screws 65 and 66 are provided which extend through suitable apertures in the spacing disc, the set screw 65 engaging a threaded aperture 67 in 25 the spacing disc 60 and the set screw 66 engaging the surface of the disc.

An angle bracket 68 (Fig. 4) is mounted upon the left-hand surface of the disc 60 as viewed in Fig. 2 and is secured thereto by 30 suitable bolts 69—69. Through an enlarged head 71 of the bracket, an elongated bolt or shank member 72 extends, upon the extremity of which is adjustably secured a clamp 74 which carries a guide roller 75. Adjacent 35 the guide roller, the plate 46 is provided with a suitable slot or aperture 76 through which passes a strand or tape 78 which is drawn from the pad holder 64 and over the guide roller. A plain bracket 79 (Fig. 2) is ad- 40 justably mounted upon the opposite side of the disc 60 by suitable bolts 80—80 and a head portion 82 thereof is provided with an elongated bolt or shank member 84. Upon an extremity of the bolt 84 a clamp 86 is ad- 45 justably secured, which supports in a position proper to carry the tape 78 from the guide roller 75 to the cable 20 at any desired point of application, a guide roller 87. The plain bracket 79 extends through a suitable 50 aperture 88 in the plate 46 whereby the roller 87 is positioned upon an opposite side of the plate 46 from the guide roller 75. A portion 55 90 of the circular pad holder 64 constitutes a drum which is engageable by a band or other suitable type of brake 91 in order to control the tension in the tape as it is being wound about the cable by pressure to vary the relative rates of rotation between the pad holder 64 and the plate 46. The plate 46 is 60 provided upon the right-hand surface, as viewed in Fig. 2, with an annular shelf 94 which is concentric with the axial aperture 51 and the bearing flanges 50. The shelf is 65 provided with an upturned edge or rim 95 which rotatably secures upon the shelf an

annular pad holder 96. A bracket 98 (Fig. 3) is mounted upon the right-hand surface of the plate 46 by suitable bolts 99 and a head portion 100 thereof is provided with an elongated arm or bolt member 103. A clamp 104 70 is mounted upon an extremity of the arm and rotatably supports a guide roller 106 by means of which tape or other suitable material 107 for serving is removed from the annular pad holder. A bracket 108 (Fig. 2) 75 is adjustably mounted upon the right-hand surface of the plate 46 by suitable bolts 110—110 and a head portion 111 thereof is provided with an adjustably secured elongated bolt or arm member 114. Upon an extremity of the arm is adjustably mounted a clamp 115 by means of which a guide roller 116 may be suitably positioned to receive the tape 107 from the guide roller 106 and direct it at any desired angle of application to the cable 20. The annular pad holder 96 is provided with a drum portion 118 which is engaged by a band or other suitable type of brake 119 for the purpose of controlling the tension in the tape 107 as it is wrapped about the cable 20. Suitably secured within the tubular portion 52 of the plate 46 and projecting to the right thereof as shown in Fig. 2 is a guide tube 120 which is provided with straight edged slots 122 and 123 respectively, for the purpose of straightening the tapes 78 and 107, immediately prior to their positioning upon the cable 20 and to effect the removal of any tendencies such as creasing, curling or twisting, etc. such as might interfere with its true disposition with reference to the cable 20.

The handling and serving of the cable 20 is considerably facilitated by use of the apparatus described above. In passing through the serving head, the cable moves in the direction indicated by the arrow in Fig. 2 through the central aperture 27 and tube 28 of the magazine 26, the tubular portion 52 of the serving head, and through the guide tube 120 wherein the tapes 78 and 107 are wrapped therearound; and the wrapped cable then passes outwardly from the head through the aperture 19 of the magazine 16.

The circular and annular pad holders and the serving head, including the guide tube 120, are concentrically disposed and are rotatably mounted about the cable 20 by the bearing support rollers 39, 39 and 42, 42. Since the supplies and supply holders are concentric with each other, with the serving head and with the cable being served, they may be rotated about their axes at any desired speed without fear of damage due to centrifugal forces. This is of great importance in practice, since the tape is often of metal and the supply pads may range from 300 to 600 lbs. each in weight.

The circular member or pad holder 64 is at all times loaded with one of the circular

pads 30, and rotates with respect to the projecting sleeve 62 and spacing disc 60 as the tape 78 is drawn therefrom by means of the sprocket and chain driving of the serving head. By varying the pressure of the brake band to vary the speed of relative rotation of the pad holder 64, the tension in the tape as it passes in succession over guide rollers 75 and 87 is directly controlled and the tape 10 may be wrapped about the cable 20 in spiral fashion as tightly as may be desired after it passes through the slotted portion 122 of the guide tube 120. Due to the fact that in traveling from the guide pulley 75 to the pulley 87, the tape 78 passes through the plate 46 by means of the aperture 76 therein, it is the first tape to engage the cable 20.

The annular pad holder 96 is at all times loaded with one of the annular pads of tape 22, and as the tape 107 is drawn from the periphery of the pad, the pad rotates with the pad holder 96 with respect to the annular supporting shelf 94, however, the rate of relative rotation is determined by the pressure of the brake 119 upon the drum 118 to control the tension in the tape. The guide spools 106 and 116 carry the tape from the periphery of the pad across the face of the serving head to the center thereof, the spools being adjustable in their respective mountings to insure that the tape passes through the slot 123 of the tube 120 and engages the cable. It will be understood that the slot 123 is farther from the plate 46 than is the slot 122. Consequently, the tape 107 engages the cable subsequent to the engagement therewith of the tape 78 and the lay of the tape 107 is so controlled that it is deposited about the cable 20 in alternate juxtaposition with respect to the prior deposited tape 78, thus insuring that every portion of the cable 20 is covered with tape.

The operation of the machine is continuous if desired, except for such stops as may be necessary for splicing or shifting new pads of tape from either of the magazines terminating usually only when the end of the cable 20 has been reached. Since such a practice usually requires more tape than is conveniently stored upon any of the pads, the magazine supplies are provided immediately adjacent the pad holders, and carry a sufficient number of pads to insure ample tape for the length of cable being served. Should the quantity of tape upon the circular pad holder 64 become exhausted, a pad 30 from the magazine may be manually moved from the tube 28 onto the pad holder 64 and the end thereof is secured to the end of the tape of the exhausted pad during its passage from the body of the new pad as it is drawn from the pad holder 64 and guide roller 75 and to the guide roller 87. Since the passage of the tape 78 through the serving head and annular shelf 94 is direct, and since it engages the

cable first, the splicing may be accomplished without interfering with the tape 107. The latter tape is drawn through the slot 123, and since that slot is farther removed from the surface of the serving head than is the slot 122 the tape 107 is served on top of that coming through the slot 122, which has already engaged the cable. Upon exhaustion of the tape in the annular pad holder 96, the material supply therefore may be replenished by manually moving one of the pads 112 over to position on the pad holder 96, and the old and the new tapes may be joined in any suitable manner without requiring severance of the tape from the circular pad holder. 20

It will be understood that the embodiment of the invention herein described and illustrated is merely a convenient and useful form thereof, and that the invention is capable of many other modifications without departing from the spirit and scope thereof as defined by the appended claims. 85

What is claimed is:

1. In a serving apparatus, a material supply, a pair of members for carrying the material and means for serving the material from one member and through the second member and from the second member to alternate juxtaposition with that served from the first member. 95
2. In a serving apparatus, a serving head, an annular member on one side thereof for serving material, and a member on the other side thereof for serving material through the annular member. 100
3. In a serving apparatus, a serving head, a member on one side thereof for serving material and having an aperture and a member on the other side thereof for serving material through the aperture of the first member. 105
4. In a serving apparatus, a serving head, a plurality of pads of serving material thereon adapted to serve the material to a common object, the axis of the pads being parallel to the axis of the serving head, and means whereby one of the pads may be replaced without interfering with the material served from the other pad. 110
5. In a serving apparatus, a rotatable serving head having an axial aperture, a circular pad of serving material mounted on the head at one side thereof and concentrically of the aperture and an annular pad of serving material mounted on the head on the other side thereof concentrically of the circular pad. 120
6. In a serving apparatus, a rotatable serving head, an annular member on one side thereof for serving material to a point axially aligned with the center of rotation of the head, and a circular member on the other side of the head for serving material through the annular member to another point axially aligned with the center of rotation of the head and in alternate juxtaposition with re- 125
- 130

spect to the material served from the annular member.

7. In a serving apparatus, a rotatable serving head having an axial aperture for accommodating the object to be served, a circular pad of serving material on one side of the head and an annular pad of serving material on the other side thereof and means operative upon rotation of the head for serving the material from the circular pad through the annular pad and from the annular pad to alternate juxtaposition with that served from the circular pad.

8. In a serving apparatus, a fixed housing, a rotatable serving head having a peripheral flange, spaced rollers in the housing and engaging the flange for carrying the serving head, a tubular shaft extending axially through the head for accommodating a relatively moving member to be served, an annular pad of tape rotatably mounted on one side of the head and concentrically of the tubular shaft for serving one layer of tape to the member, a circular pad of tape mounted concentrically thereof and rotatably on the other side of the head for serving a second layer of tape through the annular pad to the member, and a brake for varying the relative revolving speeds of one of the pads and the serving head to control the tension in the tape.

9. In a serving apparatus, a member having an aperture to accommodate an object to be served, a supply for furnishing material to be served upon the object in a plurality of strands, guide means operative to insure the application of the strands to the object at one side of the member, means disposed upon the other side of the member for forwarding one of the strands to the guide means, said strand being the first to engage the object, and means mounted upon the opposite side of the member from the first means for forwarding another strand to the guide means to engage the object in alternate juxtaposition to the first strand.

10. In a serving apparatus, a rotatable serving head, a circular pad of serving material coaxially mounted on the head at one side thereof, and an annular pad of serving material coaxially mounted on the head at the other side thereof.

11. In a serving apparatus, a rotatable serving head having an axial aperture, a circular pad of serving material and an annular pad of serving material having an axial aperture, and means for forwarding serving material from the circular pad to a point axially aligned with the aperture of the serving head through the aperture of the annular pad.

In witness whereof, I hereunto subscribe my name this 14th day of March, A. D. 1930.
